UNITED STATES PATENT OFFICE.

EDWARD GARLICK, OF KELSO, WASHINGTON.

SAND WASHER AND SEPARATOR.

Application filed April 9, 1927. Serial No. 182,477.

My present invention has reference to a sand washer and separator and the object is the provision of an apparatus for this purpose which is entirely automatic in operation.

5 A further object is the provision of a device of this character that includes a centrally pivoted box divided into a weight compartment and into a sand receiving compartment, the latter having an outlet spout on its upper portion that communicates with a flume and being provided, at its lower portion with an outstanding pipe that contacts with an element to normally close the same when the box is in normal horizontal position, while a constant flow of water is delivered through apertured pipes or nozzles in the bottom of the sand compartment which thoroughly agitates the sand and causes the muddy water to rise in the compartment and 20 wherein the weight of the sand will tilt the box to cause the sand to be delivered to a suitable receptacle through the pipe and the mud and water through the spout into the flume, the action being automatic throughout. 25 To the attainment of the above broadly stated objects and others which will present themselves as the nature of the invention is better understood, the improvement further resides in certain other novel features of construction, combination and operative association of parts, one satisfactory embodiment of which is disclosed by the accompanying drawings.

In the drawings:

35 Figure 1 is a side elevation of the improvement.

Figure 2 is a top plan view thereof.

Figure 3 is a sectional view on the line 3—3 of Figure 2.

40 Figure 4 is a sectional view on the line 4—4 of Figure 3.

As disclosed by the drawings I make use of a base that preferably comprises side beams 1 that are notched at their upper corners. 45 The notches, at the forward end of the support are deeper than those at the rear end thereof, and fitted in and secured to the beams in the last mentioned notches there is a cross piece 2 that projects above the sides of the base. Also fitted in and secured to the notches at the forward end of the sides there is another cross beam 3. This beam does not project above the side members of the base, as does the beam 2, and secured to this beam 3 50 there are plates 4 arranged in parallelism with the sides of the base, the said plates and

the end of the base adjacent thereto having fixed thereon a comparatively wide front board or plate 5. This plate extends a considerable distance above the base proper, the lower portion of the plate being provided with an opening 6 and the inner face of the plate, in a line with the longitudinal or upper wall provided by the opening 6 having fixed thereon a plate or strip 7 whose lower corner is beveled, as at 8.

Fixed centrally on the side members of the base there are bearings 9 for a shaft 10, and this shaft is fixed by suitable means, such as indicated by the numeral 11, to the bottom of a substantially rectangular box or receptacle 12. The box is centrally divided by a transverse partition 13 into compartments 14 and 15, respectively. In the compartment 15 there is a ballast 16 which normally seats the box on the transverse plate or beam 2 and thereby sustains the box in a horizontal position. The outer end wall of the compartment 15, at the upper portion thereof is provided with an outwardly directed downwardly inclined spout 17, and this spout is arranged opposite a flume, (not shown).

Passing angularly through the outer wall at the bottom of the compartment 15 there is a pipe member 18. This pipe has an outer beveled end 19 designed for engagement with the beveled corner 8 of the plate or beam 7 and whereby a water tight joint is established between the pipe 18 and the said element 7 when the box 14 is in its normal horizontal position.

Leading from the top of the compartment 15 and extending downwardly therein, there is a water conductor in the nature of a pipe 19'. This pipe has its lower end provided with couplings to which is attached two pipe members. Both of these pipe members have their outer ends plugged, one of the pipe members indicated by the numeral 20 being directed into the mouth of the valved pipe 18, the second pipe 21 being of angle formation and having an upwardly directed branch. Both the pipes 20 and 21 are apertured and in reality provide nozzles.

Any suitable means, not shown, may be provided for delivering sand into the compartment 15. Of course, it is to be understood that the sand is screened so that gravel is removed therefrom. Water which is forcibly directed through the pipe 19' and through the nozzle pipes 20 and 21 will agitate the sand in the bottom of the compartment 15 and acting on

the sand will agitate the same to remove mud therefrom. When the quantity of sand in the compartment 15 is such as to overbalance the weight or ballast 16 in the compartment 14, the box will tilt. This brings the valved pipe 18 away from its seat 8. The muddy water at the top of the compartment 15 will flow through the spout 17 while the sand will be delivered through the valved pipe 18 and will pass through the opening 6 at the front of the device. The construction is extremely simple, and the operation is automatic and continuous as long as sand is delivered into the compartment 15. A certain amount of mud may accumulate at the bottom of the compartment 15 and for this reason the outlet pipe for the valve 18 has its inner end elevated to raise the same above the bottom of the said compartment so that only sand will flow through the said pipe. The continuous tilting of the box 14 will agitate the mud that is collected in the bottom of the compartment and the constant flow of water in the said compartment will, in time dissolve such matter.

25 The advantages of the construction will be apparent to those skilled in the art to which the invention relates and while I have herein set forth one satisfactory embodiment of the improvement it is to be understood that I do not wish to be restricted to the specific details herein set forth and hold myself entitled to make such changes therefrom as fairly fall within the scope of what I claim.

30 Having described the invention, I claim:—

1. A device of the character described comprising a base, a box mounted for rocking movement thereon, weight means normally maintaining the box in horizontal position, said box being adapted to receive sand to be cleaned, a water over-flow spout at the top of the box, a sand out-let pipe at the bottom of the box, a stationary member positioned to be abuttingly engaged by the projecting outer end of said outlet pipe to form a closure therefor when the box is in normal position, and a water spray pipe located within the box and having a branch extending into said pipe.

2. A device of the character described comprising a base, a box mounted for vertical rocking movement thereon, weight means normally maintaining the box in horizontal position, said box being adapted to receive sand to be cleaned, a water over-flow spout at the top of the box, a sand outlet pipe at the bottom of the box projecting therebeyond and having a beveled end, a stationary member carried by the base and shaped for conforming engagement with the projecting beveled end of the pipe to form a closure therefor when the box is in normal position, and a water spray pipe extending into the box and into the pipe for cleaning and agitating the sand, said pipe having its inner end located above the bottom of the box to avoid the out-flow of any accumulation of mud.

In testimony whereof I affix my signature.
EDWARD GARLICK.
